US0D1074598S

(12) **United States Design Patent** (10) **Patent No.:** **US D1,074,598 S**
(45) **Date of Patent:** **** May 13, 2025**

(54) **BATTERY BOX**

(71) Applicant: **MICROVAST POWER SYSTEMS CO., LTD.**, Huzhou (CN)

(72) Inventors: **Weisong Chen**, Zhejiang (CN); **Ting Chen**, Zhejiang (CN); **Bin Li**, Zhejiang (CN); **Cheng Zhong**, Zhejiang (CN)

(**) Term: **15 Years**

(21) Appl. No.: **35/520,799**

(22) Filed: **Mar. 29, 2024**

(80) **Hague Agreement Data**

Int. Filing Date: **Mar. 29, 2024**

Int. Reg. No.: **DM/236770**

Int. Reg. Date: **Mar. 29, 2024**

Int. Reg. Pub. Date: **May 10, 2024**

(51) **LOC (15) Cl.** **13-02**

(52) **U.S. Cl.**

USPC **D13/119**

(57) **CLAIM**

The ornamental design for a battery box as shown and described.

DESCRIPTION

1. Battery box

1.1 : Front

1.2 : Back

1.3 : Left

1.4 : Right

1.5 : Top

1.6 : Bottom

1.7 : Perspective

1.8 : Perspective

1.9 : Enlarged

1.10 : Enlarged

1.11 : Enlarged

1.12 : Enlarged

1.13 : Enlarged

Fig. 1.9 is an enlarged view of part 9 in fig. 1.7; fig. 1.10 is an enlarged view of part 10 in fig. 1.7; fig. 1.11 is an enlarged view of part 11 in fig. 1.7; fig. 1.12 is an enlarged view of part 12 in fig. 1.8; and fig. 1.13 is an enlarged view of part 13 in fig. 1.8; the broken lines consisting of evenly spaced dash lines depict portions of the battery box that form no part of the claimed design.

1 Claim, 13 Drawing Sheets
